FEEDING MECHANISM

Joseph Stuart, II, Wilmington, Del., assignor to
 Hercules Powder Company, Wilmington, Del.,
 a corporation of Delaware

Application September 28, 1939, Serial No. 296,962

4 Claims. (Cl. 140—125)

This invention relates to a feeding mechanism and more particularly to a mechanism for feeding strands or filaments of relatively small diameter at a definite rate and under controlled tension.

The manufacturer of devices such as electric firing devices, electric bulbs, radio tubes, etc., are faced with the problem of feeding filaments of relatively small diameter to the various operations. These filaments are not sufficiently stiff to prevent curling and are therefore very difficult to handle. Many attempts have been made to provide a simple and effective means for feeding the necessary sections of filaments to the devices being manufactured but these have not been entirely successful in obtaining a mechanical device which will operate efficiently. Thus, for example, in the manufacture of blasting caps, the electric firing devices contain a high resistance element which is normally composed of a very fine platinum alloy wire. This wire element which is normally between 0.001 and 0.002 inch in diameter is obtained from a spool of wire and the lengths have a decided tendency to curl tightly upon itself. The wire is, of course, very fragile due to its relatively small diameter and this with its curling characteristic makes various operations with it extremely difficult. At present the element is normally soldered or welded to the proper terminals by highly skilled labor, and this process is very tedious, slow and exacting on the operators.

The present invention aims to provide a suitable mechanism for feeding the filaments of relatively small diameter to the various types of operations at the correct speed and under the desired tension. The provision of such a feeding device will fill a long needed want in various industries.

The object of the present invention is therefore to provide a mechanical means of delivering a strand or filament to any desired operation.

A further object of this invention is to provide a mechanical means of feeding a strand by which a section of the strand supported at each end is presented to an operation.

A further object of this invention is to provide a means of feeding a high resistance wire of relative small diameter to a soldering or welding unit of, for example, an electric firing device assembly machine.

A still further object of this invention is to provide a mechanism which will prevent waste of the filaments being used.

A still further object of this invention is to pro-

vide a mechanism which presents section of a filament under the desired tension to an operation.

Other and further objects of this invention will be obvious upon an understanding of the illustrative embodiment about to be described or will be indicated in the appended claims.

A preferred embodiment of this invention has been chosen for purpose of illustration and description and is shown in the accompanying drawing, forming part of the specification wherein,

Figure 1 is a side elevation of the feeding mechanism.

15 Figure 2 is a partial cross-sectional view taken along line 2—2 on Figure 1 and shows the spider leg clamping means in the position of picking up a wire; and

Figure 3 is a partial cross-sectional view taken 20 along line 3—3 on Figure 1 and shows a device for cleaning scraps of wire from the clamping means or spider legs.

Described generally, the machine embodying the present invention for feeding filaments or 25 strands of relatively small diameter comprises means for guiding the strand to a rotatable pick-up means such as a pick-up spider which has a series of clamping means designed to receive and engage the strand. There is suitable 30 means such as a cam located in proper relation to the strand guide and rotatable pick-up to effect the opening of the clamping means and cause them to receive and engage the strand. The strand is thus fed through the guide to 35 the rotatable means and engaged at successive points thereby presenting a series of supported sections of the strand to any specific operation such as a welding unit or the like. At the operation, the supported section of wire is used and 40 then severed in a suitable manner at the proper points. A device such as a knife edge wedge is located at a point just after the welding or similar operation and cleans any scrap of filament from between the clamping means if such scrap 45 remains therein. The clamping means then returns to the guide and again clamps the filament.

Referring again to the drawing, there is shown a machine in which a strand or filament 1 of relatively small diameter enters the feeding 50 mechanism which includes a support bar 2 upon which is mounted a strand guide 3 comprising a member 4 attached to the support bar 2 and upon which is positioned members 5 and 6 in a manner so as to form a narrow directing channel 7 through which the strand 1 is led to a pick-up

spider 8. The members of the strand guide 3 are fastened into position by suitable means such as screws or bolts shown as 3A.

The strand 1 entering the guide 3 may be obtained from a spool or similar reserve, not shown, which may be, if desired, mounted on the support bar 2 at any convenient point. I have found it desirable to mount the spool with a braking or drag device attached thereto so that it may keep the strand under a very slight tension. This braking action or drag prevents free running of the spool and backslashing of the strand and allows the strand to be kept under controlled tension throughout the feeding operation.

The strand 1 leaving the channel 7 is picked up by the spider 8 which preferably comprises a rotatable substantially non-yielding spider disc 9 and a spring leaf 10 which may have a similar contour as the spider disc and coacts therewith to clamp the strand 1 at predetermined points. The spider disc 9 also has a pin or projection 11 adjacent the outer end of each leg upon which the spring leaf 10 bears.

As shown more particularly in Figures 2 and 3, it will be noted that the spring leaf 10 is of double construction, while I have found this method of construction preferable, I may also use a single leaf construction or a multiple leaf construction depending only upon the use and dimensions of the spring leaf.

In these figures it will also be noted that I have indicated that pins 11 are inserted in the end of each spider leg for the spring leaf to bear upon, but it is to be understood that I may use a boss or projection of any suitable type in place of a pin. The boss or projection may, if desired, be cast on the spider legs.

The operation of opening the spring leaf 10 from the pins 11 is accomplished by a fixed cam 12 which may be integral with members 5 and 6 of the guide. The spring leaf 10 is shown only partially cross-hatched and indicated by a ghost line for clarity in Figure 12. The cam 12 acts in a manner to move spring leaf 10 away from the spider disc 9 and the pin 11, and so allows the strand 1 to be led between the pin and spring leaf between which it is tightly clamped when the spring leaf is released when the end of the cam 12 is reached. The further rotation of the spider draws the wire out from the guide and brings another leg of the spider into position to clamp the wire. Thus, is provided a section of wire supported at both ends and under controlled tension.

The strand is therefore clamped between the pin projecting from the rigid spider disc and the spring leaf at regular intervals and carried in this manner under controlled tension to a station 13 for use. The station 13 may be, for example, a welding device that uses the section of strand, which may be a fine wire, for bridging the two terminals 14.

It is to be understood that I contemplate either moving the feeding mechanism to the welding station 13 or the welding station to the feeding mechanism whichever is more convenient. Further, that I have indicated the wire being fed to a welding station only by way of illustration and that I may feed the wire in a similar manner to any desired operation such as, for example, a soldering station, a station for transferring the wire to other operations or similar operations that require fine wire under controlled tension. Further, I may, if desired, cut the wire after welding it to the terminal or in other ways sever it

to produce neat operations. This severing operation may leave scraps of wire between the pins and spring.

After the welding or similar operation, there thus is usually a small scrap of the strand 15 remaining between the pin and the spring leaf. In order to remove this scrap of the strand 15 a scrap ejector 16 is mounted on the support bar 2 and comprises a knife edge wedge 17 which is shaped and positioned to enter between the spring leaf 10 and the pin 11 and remove the scrap 15, Figure 3. The wedge is attached to a rigid support 18, by means 19 which support is fastened to the main support bar 2.

The spring leaf 10 is held in the desired resilient compressive relation against the pins 11 of the disc by a washer 20 and adjusting means 21. The adjusting means 21 shown may be designed to individually control the tension of each clamping means if so desired.

The relative position of the strand guide and scrap ejector with reference to the circumference of the spider is shown in Figure 1 to be approximately diametrically opposite each other. This is not essential but is only so shown for clarity. It is, therefore, to be understood that I contemplate positioning the guide and ejector at the most desirable points for performing their functions while the strand is delivered to the specific operation desired. The scrap ejector may, if desired, be combined with the spreading cam but I prefer to use a separate station to perform this operation.

It will be obvious to those skilled in the art that I may motivate the shaft upon which the rotatable spider is mounted in many ways such as by a motor, by gears, ratchet, or manually. I prefer to drive the shaft by ratchet means as in this manner the speed and length of movement are easily controlled.

It is to be understood that wherein this specification and claims I refer to strand or filaments I include strands and filaments having irregular cross-sections, for example, rectangular, polyhedral or ribbon like as well as the normal strands and filaments having a substantially circular cross-section.

It will be seen that the present invention provides a simple efficient machine for feeding strands of relatively small diameter to any particular operation and particularly for feeding high resistant wire of the type used in electric blasting caps to a welding station. The machine is very simple but effectively feeds those strands which are fragile and tend to curl tightly upon themselves.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

What I claim and desire to protect by Letters Patent is:

1. In a device for feeding a strand having relatively small diameter, the combination of means for guiding a strand, a rotatable spider adjacent said guiding means comprising a series of substantially radially extending legs and a clamping member on each of said legs and adapted to engage the strand and hold it against and adjacent the end of said legs, and means for operating said clamping members to cause them to receive and engage the strand.

2. In a device for feeding a strand having a relatively small diameter, the combination of means for guiding a strand, rotatable means adjacent said guiding means comprising a substantially non-yielding spider having legs provided with a projection adjacent the ends thereof and a spring member on each leg bearing upon the projection, and a cam for moving the spring members away from the projections to receive and then engage the strand.

3. In a device for feeding a strand having a relatively small diameter, the combination of means for guiding the strand, a rotatable spider adjacent said guiding means, having a series of substantially radially projecting members, a resilient clamping member on each of said projecting members normally engaging said projecting members adjacent the ends thereof and

adapted to engage portions of the strand and clamp it against said ends of said projecting members, and means for operating said clamping members to cause them to receive and engage the strand.

4. In a device for feeding a strand having a relatively small diameter, the combination of means for guiding a strand, rotatable means adjacent said guiding means comprising a substantially non-yielding spider having legs provided with a projection adjacent the ends thereof and a spring member on each leg bearing upon the projection, and a cam for moving the spring members away from the projections and receive and then engage the strand and means for removing scraps of the strand from between said projection and spring member.

JOSEPH STUART, II.
